Mr. T. H. Alexander Atty.*

United States Patent Office.

E. R. HALL, OF UTICA, ASSIGNOR TO HIMSELF, AND D. M. GOLDEN, OF FRANKFORT, AND B. G. EATON, OF MEXICO, NEW YORK.

Letters Patent No. 76,441, dated April 7, 1868.

IMPROVED CLOTHES-DRIER.

The Schedule referred to in these Letters Patent and making part of the same.

TO ALL WHOM IT MAY CONCERN:

Be it known that I, E. R. HALL, of Utica, in the county of Oneida, and State of New York, have invented certain new and useful Improvements in Clothes-Drier; and I do hereby declare that the following is a full, clear, and exact description thereof, reference being had to the accompanying drawings, and to the letters of reference marked thereon, which form a part of this specification, in which—

Figure 1 represents a vertical section of my clothes-drier.

Figure 2 is a front elevation of the same.

Figure 3 is a side view of the shaft and spools.

The letter A represents the body of my drier, and B B two boxes, placed on opposite sides of A. The object of said boxes will be hereinafter explained. C designates an elevator, which occupies the interior of the body or case A, and allowed to play with a vertical motion. D represents a shaft, which works near the bottom of case A; the said shaft being furnished with three spools, e. Fastened to the top of elevator is an attachment, E, which is furnished on each of its four sides with two vertical projections, g. In the cavity formed between each pair of said projections, the ends of the arms h are placed, and allowed to play on pivots that secure them to projections g. Directly behind the end of each arm h is placed the spring s, the object of which will be hereafter explained. Each of arms h is furnished with a hinged extension, m, which can be folded back when required. n represents a friction-pulley, connected with each arm h, the use of which will be shown hereafter. It will be observed that the arms h have numerous perforations, into which rods or hooks can be inserted for supporting clothes. F represents four pulleys, two of which are pivoted in each box B, (see fig. 1,) one near the top, and the other near the bottom of said box or boxes. D represents the spool-shaft, on which are the three spools e, as above stated. To the middle spool e, two tape-lines, i, are fastened, one of said lines being attached to the top and the other to the bottom of said spool. The lines i are carried from spool e to the friction-pulleys F and F', and thence over the upper pulleys F, and fastened to elevator C, (shown in fig. 1.) f represents a tape-line, of which there are two, one being attached to each of the outside spools e. The upper ends of said lines are fastened to the bottom of elevator C, and are intended to arrest the upward motion of said elevator, when it has reached the desired height. k represents a ratchet-wheel, placed on shaft D, outside of case A, the design of which is to hold the elevator in firm position when it is at the top of case A. H designates the pawl, for holding the ratchet-wheel.

The operation of my machine is as follows: When the elevator is at its lowest position in case A, by moving the crank on shaft D from left to right, the two tape-lines i will be wrapped around the centre spool e, and as the said lines are shortened by being taken up by the spool, to the same degree will the elevator be carried upwards, until it reaches the top of case A, when the arms, being released from confinement in said case, will be thrown in a horizontal position by the action of the spring s. By reversing the motion of the crank, the arms h will be brought again to a vertical position, so as to descend in case A. The object of the pulleys n, on arms h, is to facilitate the motion of said arms when ascending in case A.

It will be observed that the top of the frame A, marked R, is adjustable, and only placed in position when the drier is not in use.

Having thus described my invention, what I claim, and desire to secure by Letters Patent, is—

1. The springs s s s s, for throwing out the arms h h, substantially in the manner specified.
2. The combination of the elevator C, springs s s s s, and arms h h, substantially as and for the purpose set forth.
3. Arms h h, springs s s, elevator C, spools e e, and tape or cords f, all combined and arranged substantially in the manner and for the purpose described.

In testimony that I claim the foregoing as my own, I affix my signature in presence of two witnesses.

E. R. HALL.
